(57) CLAIM

I, claim the ornamental design for an airless pump dispenser for cosmetic materials, as shown and described.

DESCRIPTION

FIG. 1 is a front elevational view of an airless pump dispenser for cosmetic materials embodying my design and shown without the cover.

FIG. 2 is a rear elevational view thereof;

FIG. 3 is a right side elevational view thereof, the left side view being a mirror image;

FIG. 4 is a top plan view thereof;

FIG. 5 is a bottom plan view thereof;

FIG. 6 is a front elevational view of the airless pump dispenser for cosmetic materials shown with the cover, the rear view being a mirror image; and,

FIG. 7 is an exploded perspective view thereof.

The airless pump dispenser for cosmetic materials is shown with and without the cover for convenience of illustration.

The broken lines are for environmental purposes only and form no part of the claimed design.
